UNITED STATES PATENT OFFICE.

FRED W. PETERS, OF OAKMONT, PENNSYLVANIA, ASSIGNOR TO VERONA TOOL WORKS, OF PITTSBURGH, PENNSYLVANIA, A CORPORATION OF PENNSYLVANIA.

RAIL ANCHOR.

Application filed September 12, 1922. Serial No. 587,725.

To all whom it may concern:

Be it known that I, FRED W. PETERS, a citizen of the United States, residing at Oakmont, county of Allegheny, State of Pennsylvania, have invented a new and useful Improvement in Rail Anchors, of which the following is a full, clear, and exact description.

The present invention relates broadly to rail anchors of that class having a clamping engagement with a rail base and a cooperating engagement with a tie to check longitudinal creeping of the rail.

It has heretofore been proposed to construct rail anchors effective as levers, and having a loop engaging one flange of a rail together with means for exerting an upward flexing pressure on the edge of the rail flange. Such constructions have destroyed the true shape of the rail to which they were applied. By the present invention there is provided a rail anchor which, while engaging one flange of a rail base, and in certain instances slightly movable about its point of engagement as a fulcrum, is effective for laterally clamping the rail as distinguished from crimping or flexing the same. This insures a firm hold on the rail without any objectionable bending. Furthermore, it is desirable to provide a rail anchor which may be easily constructed, quickly applied, and reused as may be found necessary.

In the accompanying drawings there are shown for purposes of illustration only certain preferred embodiments of the present invention, it being understood that the drawings do not define the limits of my invention, as changes may be made in the construction and operation therein illustrated without departing from the spirit or scope of my broader claims.

In the drawings:

Figure 1 illustrates a rail section having one form of rail anchor applied thereto;

Figure 2 is an edge view of the rail anchor itself with the key removed therefrom;

Figure 3 is a perspective view of the key;

Figure 4 is a view, corresponding to Figure 1, illustrating a slightly different form of rail anchor;

Figure 5 is a view corresponding to Figure 1, illustrating a further embodiment of the invention, and

Figure 6 is a perspective view of the rail anchor illustrated in Figure 5.

Referring more particularly to the drawings, there is illustrated in Figure 1 a section of a standard rail 2 having a rail anchor constructed in accordance with one embodiment of the invention applied thereto. This rail anchor comprises a main body portion 3 which is preferably formed from a relatively flat imperforate bar of suitable material. While the rail anchor may be of forged or wrought metal, it will be obvious that if desired it may be formed by casting or in any other well known manner.

Formed on one end of the body portion 3 is a flange engaging loop 4 adapted to receive one edge of the rail base flange. The opposite end of the body portion may be shaped to provide a head 5 either with or without the reinforcing rib 6. The head 5 preferably extends upwardly from the main body portion a sufficient distance whereby when the rail anchor is applied, a portion of the head will lie in the horizontal plane occupied by the rail base flange. As the rail base flange engaging loop 4 need not be formed to provide an accurate and tight fit with the base flange of the rail, it will be apparent that the anchor may be easily applied.

In the form of the invention illustrated more particularly in Figures 1 and 2 of the drawings, the head 5 has key receiving shoulders 7 which extend at a slight angle with respect to a vertical plane, the angle being such that the shoulders diverge upwardly and outwardly from such plane. Adapted to cooperate with the inclined shoulders 7 is a wedge-shaped key 8 which is preferably bifurcated throughout a portion of its length to provide portions adapted to straddle the rib 6, where such rib is provided, and a portion of the body 3.

As the key 8 is driven into position between the shoulders 7 and the edge of the rail base flange, it will be apparent that the rail anchor is bodily moved laterally in such manner that the loop 4 more firmly engages the edge of the rail base flange embraced thereby. By reason of the upward extension of the head 5, there is provided a second bearing surface in the plane of the rail base flange, whereby the base of the rail is firmly clamped.

As the loop 4 is not necessarily accurately formed, the body portion 3 of the rail anchor is permitted to drop into the inclined position shown thereby providing an engagement with a tie 9 below the extreme upper edge of the tie. This is desirable as the tie is thereby prevented from any objectionable rolling.

In Figure 4 there is illustrated a slightly modified form of the invention in which parts corresponding to the parts already described are indicated by the same reference characters having a prime added thereto. In this embodiment of the invention the rib 6 is omitted and the shoulders 7' extend in a vertical direction. In some instances this construction has been found desirable as driving the key 8' into position does not effect any turning movement 20 of the rail anchor about its fulcrum point within the loop 4'.

Figures 5 and 6 illustrate still another modified form of the invention, and for sake of brevity parts corresponding to the parts already referred to in connection with Figures 1 to 3 are indicated by the same reference characters having a one prefixed thereto. In this form of the invention the shoulders 17 are inclined in the opposite direction whereby as the key 18 is driven into position the body of the rail anchor will be drawn upwardly against the bottom of the rail base simultaneously with the lateral movement of the rail anchor which effects the desired clamping of the rail base.

By providing a rail anchor with a head as disclosed herein and using therewith a bifurcated key, it is possible to obviate the necessity of forming the rail anchor with a separate key receiving loop or opening. This has decided advantages in the manufacture of the anchor, as the cost thereof may be decreased. At the same time, due to the construction of the key, a wide bearing 45 surface between the key and the rail base flange is provided.

I claim:

1. In a rail anchor, a body portion having a rail base flange engaging loop on one end thereof, a head on the opposite end, and a bifurcated key adapted to straddle said body portion and extend between the rail base flange and the head, substantially as described.

2. In a rail anchor, a body portion having a rail base flange engaging loop on one end thereof, a head on the opposite end, and a wedge-shaped bifurcated key adapted to straddle said body portion and extend be-

tween the base flange and the head, substantially as described.

3. In a rail anchor, a body portion having a rail base flange engaging means on one end thereof, a head on the opposite end, and a bifurcated key adapted to straddle the body portion and extend between the base flange and the head, said key being tapered to move the body of the rail anchor laterally as the key is driven into position, substantially as described.

4. In a rail anchor, a body portion having a rail base flange engaging means on one end thereof, a head on the opposite end projecting upwardly from the body portion, and a bifurcated key adapted to straddle the body portion and extend between the base flange and the head, substantially as described.

5. In a rail anchor, a body portion having a rail base flange engaging means on one end thereof, a head on the opposite end, said head providing inclined key engaging shoulders, and a bifurcated key adapted to straddle the body portion and extend between the base flange and said shoulders, substantially as described.

6. In a rail anchor, a body portion having a rail base flange engaging means on one end thereof, a head on the opposite end, said head providing inclined key engaging shoulders, and a bifurcated key adapted to straddle the body portion and extend between the base flange and said shoulders, said key being tapered to move the body of the rail anchor laterally as the key is driven into position, substantially as described.

7. In a rail anchor, a flat body portion adapted to extend beneath a rail base flange, said body portion having a flange engaging loop on one end thereof and an upwardly projecting head on the opposite end, and a bifurcated key adapted to straddle the body portion and extend between the base flange and the head, substantially as described.

8. In a rail anchor, a flat body portion adapted to extend beneath a rail base flange, said body portion having a flange engaging loop on one end thereof and an upwardly projecting head on the opposite end, and a bifurcated key adapted to straddle the body portion and extend in a vertical direction between the base flange and the head, substantially as described.

In testimony whereof I have hereunto set my hand.

FRED W. PETERS.
